CABINET CATCH

Fred Gerson, Elmhurst, N. Y., assignor to Akron Hardware Mfg. Corp., Woodside, N. Y., a corporation of New York

Application April 18, 1952, Serial No. 283,040

5 Claims. (Cl. 292—75)

1

This invention relates to a cabinet catch and more particularly to a cabinet catch of the type having a resilient roller engageable with a cabinet panel or catch plate to hold the cabinet door in closed position while at the same time allowing the door to be opened against the pressure exerted by the roller.

It is an object of this invention to provide a cabinet catch in which a roller and the spring means which resiliently urges the roller into engagement with a cabinet panel are quickly and easily assembled in the supporting frame and which may be readily disassembled to permit replacement of the roller or spring—both assembly and disassembly being accomplished without the use of tools. Another object of the invention is to provide a catch in which the roller will operate without binding or sliding over the engaging surface in the event the catch is tilted at an angle to the engaging surface or strike. Still another object is to provide a catch structure in which the roller pin or shaft is free to rock rearwardly about either end of the shaft so that the roller will assume a parallel alignment with the surface of strike in the event the catch is tilted at an angle to the strike or engaging surface. A further object is to provide a catch frame having L-shaped recesses in opposite side walls thereof adapted to receive the ends of the roller shaft, whereby the roller and shaft are easily inserted and removed from the catch frame by movement through the recess, while when in position within the recess, the roller is held against accidental dislodgement by the action of a spring means. Still a further object is to provide a generally U-shaped spring member having forwardly-extending arcuate arms that engage opposite end portions of the roller shaft so that the roller may be rocked rearwardly about either end of the shaft against the urging of the spring member. Additional objects and advantages will appear as the specification proceeds.

An embodiment of my invention is illustrated in the accompanying drawing, in which—

Figure 1 is a perspective view of a cabinet catch incorporating my invention; Fig. 2, a perspective view of the catch; Fig. 3, a cross-sectional side view of the door catch and catch plate in position upon a cabinet door; Fig. 4, a sectional view taken along the line 4—4 of Fig. 3; and Fig. 5, an exploded perspective view showing the parts of the catch in spaced-apart relation.

Briefly, the door catch of my invention in-

cludes a frame or body portion 10, a spring 11, and a roller and shaft assembly 12. The frame 10 is formed with a top wall 13, side walls 14 and 15, and a rear wall 16 provided with an inwardly-struck cleat 17. The side walls 14 and 15 are equipped with integral flange portions 18 and 19. The flanges 18 and 19 have elongated apertures 20 and 21 therein which receive screws 22 for holding the catch securely to a cabinet door. The elongation of the slot or aperture permits the catch to be accurately aligned before the screws 22 are finally secured tightly in place.

The side walls 14 and 15 have forwardly-extending ears or lips 23 and 24 formed integrally therewith. Each of the ears 23 and 24 is provided with a channel or recess or way 25 and 26. The recesses or ways are L-shaped and each has a base 27 and a stem 28.

The roller assembly 12 includes a roller 29 which may be made of any suitable material, but preferably it is formed from a resilient material that will permit the roller to roll smoothly and noiselessly over an engaging surface without marring or otherwise injuring the surface. The roller 29 is equipped with a centrally-aligned axle or shaft 30. The roller 29 may be rotatably mounted upon the shaft 30, or it may tightly grip the shaft to prevent rotation of the roller with respect to the shaft. The length of the shaft 30 is such that the ends thereof are readily receivable within the L-shaped recesses 25 and 26. The width of the roller 29 is, of course, somewhat narrower than the space provided between the spaced-apart ears 23 and 24 so that it may be received therebetween.

The spring member 11 has a U-shaped portion 31 having integral elongated arms 32 and 33 that extend forwardly and have an arcuate shape. The arms 32 and 33 terminate in slightly bent ends that provide hooks or crooks 34 and 35. The shape of crooks 34 and 35 is such that they accommodate the end portions of the roller shaft 30.

The catch is assembled by inserting the ends 45 of the roller shaft 30 into the stem portion 28 of the L-shaped recesses 25 and 26. The shaft 30 and the roller 29 mounted thereon are moved through the stem portion 28 of the recesses 25 and 26 and into the base 27 of the recesses. The spring member 11 is tilted so that the crooks 34 and 35 may be inserted between the roller 29 and the ears 23 and 24 and into engagement with the roller shaft 30. The U-shaped portion 31 of the spring member is then pressed between the side walls 14 and 15 where it slides against

the cleat 17 provided in the rear wall 16. The rear or U-shaped portion 31 of the spring slides against the cleat 17 until it snaps free thereof and against the rear wall 16. The cleat 17 is then effective to prevent the spring from moving in the opposite direction, since the cleat 17 will engage the U-shaped portion 31. It has been found that it is not necessary to exert extreme care in placing the crooks 34 and 35 against the roller shaft 30 prior to and during the movement of the U-shaped portion 31 against the cleat 17. The crooks 34 and 35 are adequate to prevent the spring member from sliding free of the shaft 30 during insertion of the spring.

Alternatively, the roller shaft may be inserted within the frame 10 by first inserting the U-shaped portion 31 of the spring member between the side walls 14 and 15 and against the portion of the rear wall 16 beyond the cleat 17. The roller shaft 30 is then placed in position against the crooks 34 and 35 of the spring member and then, while in engagement, urged through the stem 28 of the L-shaped recesses and into the base 27 of the recesses. I have found, however, that the method of assembly first described is more satisfactory and that the assembly may be effected with less effort and there is less danger of the spring member's slipping free of the roller shaft 30.

When assembled, the catch may be secured to a cabinet door 36 (as seen in Fig. 3) by the screws 22. The catch may be used in conjunction with a catch plate 37 secured to a stationary panel 38 of the cabinet by a screw or nail 38a. The catch plate 37 is provided with a channel 39 adapted to receive the roller 29. When the roller 29 is within the channel 39, the spring member 11 is slightly compressed and the roller is therefore resiliently urged against the catch plate and is effective to hold the door 36 in closed position. The door catch of my invention can, however, be used without a catch plate 37, and to this end, a cabinet panel may be equipped with an integral groove or recess that is adapted to receive the roller 29 when the door is in closed position.

Although the elongated slots or apertures 20 and 21 in the flanges 18 and 19 permit the catch to be properly aligned with the surface of strike, such as the catch plate 37, it may happen that a defect in the panel (for example, a knot in a wooden cabinet door) may prevent a screw 22 or other fastening device from being inserted in proper alignment with a screw 22 in the opposite flange. If this occurs, the frame 10 will be tilted slightly and the roller 29 will not be parallel with the surface of strike. This is not serious in the door catch of my invention, since the independent action of the elongated arms 32 and 33 of the spring member 11, as they engage opposite end portions of the roller shaft 30, permits either end of the shaft 30 to pivot or rock rearwardly in the base 27 of the L-shaped recesses 25 and 26 about the opposite end of the shaft, and the roller 29 is consequently self-aligning and will always run parallel to the surface of strike. To facilitate the rocking or pivoting of the roller and shaft, the roller 29 is somewhat more narrow in width than the distance between the spaced-apart ears 23 and 24 of the side walls. The roller 29 is therefore free to rock within this space.

It is an extremely simple matter to disassemble the roller 29 and shaft 30 from the frame 10 in the event that it is necessary to replace the roller or spring, etc. It is only necessary to press against the roller 29 and force the shaft 30 to

move rearwardly through the base portions 27 of the recesses 25 and 26 and then through the stem portion 28 of the recesses until the shaft 30 is free. Thus, it is seen that both assembly and 5 disassembly are quickly and easily accomplished without the use of tools, etc.

My door catch is of simple design and is very inexpensive to produce and assemble. The frame 10 may be stamped or otherwise formed from metal. It is also possible to construct the frame 10 of a plastic or other material, since the frame is subjected to very little stress and strain during the operation of the catch, the spring member 11 resting against the solid rear wall 16 assuming most of the force exerted against the roller 29 as the door is closed or opened. The roller shaft 30 may be free to rotate within the base 27 of the L-shaped recesses 25 and 26, and in such case the roller 29 may be fixed to the roller shaft 30 so that there will be no relative motion therebetween. However, it has been found more satisfactory to permit the roller 29 to rotate upon shaft 30, and also to permit the shaft 30 to rotate within the L-shaped recesses. 25 The roller shaft may be provided with grooves adjacent the ends to receive the crooks 34 and 35 of the spring member 11. It is not, however, essential and a tight mating of the roller shaft and spring member is accomplished without such grooves.

30 The door catch may be secured to a cabinet door in any appropriate position. The catch operates satisfactorily whether it is positioned upon the cabinet door to engage a stationary top, bottom or side wall of a cabinet, or a stationary shelf within the cabinet.

While in the foregoing specification I have set forth in considerable detail a single structure and method of assembly for the purpose of illustrating an embodiment of my invention, it will be understood that such details of structure and method of assembly may be varied widely by those skilled in the art without departing from the spirit of my invention as defined in the appended claims.

45 I claim:

1. In a door catch for cabinets, a frame having spaced-apart side walls adapted to receive a roller therebetween, an L-shaped channel in the forward portion of each of said side walls and aligned to receive the ends of a roller shaft therein, the base of said channels extending forwardly to a point adjacent the edges of said side walls, a roller shaft having a roller mounted thereon supported within said channels, and a U-shaped spring having forwardly-extending arms engaging said shaft and resiliently urging the same forwardly in the base of said L-shaped channels, the stem of each of said channels extending to an edge of the side wall it is in for insertion and removal of the roller-equipped shaft from said frame.

2. The structure of claim 1 in which said roller is narrower than the space between said side walls, and the arms of said spring are in engagement with the end portions of said axle, whereby said axle may pivot rearwardly about either end against the action of said spring.

3. A door catch for cabinets, comprising a 70 frame providing a top wall, spaced apart side walls, and a rear wall abutting said side walls and forming a closure for the rear end thereof, said side walls being equipped with laterally-extending flanges having apertures therein for receiving fastening means to secure said catch

to a door, said side walls having forwardly-extending ear portions provided with longitudinally-extending guideways, a roller axle extending into said guideways and movable longitudinally thereof, a roller carried by said axle and having its sides slightly spaced inwardly of said side walls, whereby said roller may be rocked upon said axle to cause one end of said axle to move rearwardly while the other end of the axle remains in a forward position, and a U-shaped spring having a rear portion engaging the rear wall of said frame and bowed arms extending forwardly adjacent the side walls of the frame and provided at their ends with crooks engaging the end portions of said axle.

4. A door catch for cabinets, comprising a frame providing a top wall, spaced-apart side walls, and a rear wall abutting said side walls to form a closure therefor, said side walls being equipped with laterally-extending flanges having apertures therein for receiving fastening means to secure said catch to a door, said side walls also having forwardly-extending ear portions having longitudinally-extending guideways therein, an axle having its ends mounted within said guideways to permit longitudinal movement of said axle, a roller rotatably mounted upon said axle and lying slightly between and spaced from said side walls, and a U-shaped spring having a flat rear portion resting against the rear wall of said cabinet and having forwardly-extending spring arms lying adjacent said side walls and provided at their ends with crook portions receiving said axle and normally urging

said axle in a forward direction, said roller being rockable upon said axle to cause one end of said axle to recede within its longitudinal guideway while the other end of the axle remains in a forward position under the force of the spring, said latter spring arm being braced against the side wall of said frame during the rocking of said roller.

5. In a door catch, a frame having spaced side walls providing a space therebetween, an L-shaped guideway in each of said side walls adapted to receive the ends of a roller shaft, a roller shaft equipped with a roller within said guideways, and spring means resiliently urging said shaft forwardly in the base of said L-shaped guideways, the base of each guideway extending forwardly and the stem of each guideway extending to the bottom edge of the side wall for the insertion and removal of said shaft from the frame.
